COMBINED WORK BENCH AND DESK OR SIMILAR ARTICLE

Stephen U. Winig, Penn Valley, Pa.
(400 Fawnhill Lane, Narbeth, Pa. 19072)

Filed Nov. 19, 1973, Ser. No. 417,834

Term of patent 14 years

Int. Cl. D6—04

U.S. CL. D6—161

FIG. 1

FIG. 2

FIG. 3

FIG. 6

FIG. 4

FIG. 7

FIG. 5

FIG. 1 is a perspective view of a combined work bench and desk embodying my new design.

FIG. 2 is a top plan view thereof.

FIG. 3 is a bottom plan view thereof.

FIG. 4 is an end view taken along line 4 of FIG. 1.

FIG. 5 is a side elevational view taken along line 5 of FIG. 1.

FIG. 6 is an end view taken along line 6 of FIG. 1.

FIG. 7 is a side elevational view taken along line 7 of FIG. 1.

I claim:

The ornamental design for a combined work bench and desk or similar article, as shown.
